(57) **CLAIM**

The ornamental design for a hoodie with accessories, as shown and described.

DESCRIPTION

FIG. 1 is a perspective view of a hoodie component of a hoodie with accessories showing my new design;
FIG. 2 is a front elevational view of the hoodie component of the hoodie with accessories of FIG. 1;
FIG. 3 is a rear elevational view of the hoodie component of the hoodie with accessories of FIG. 1;
FIG. 4 is a left side elevational view of the hoodie component of the hoodie with accessories of FIG. 1;
FIG. 5 is a right side elevational view of the hoodie component of the hoodie with accessories of FIG. 1;
FIG. 6 is a top plan view of the hoodie component of the hoodie with accessories of FIG. 1;
FIG. 7 is a bottom plan view of the hoodie component of the hoodie with accessories of FIG. 1;
FIG. 8 is a perspective view of a pouch accessory component of the hoodie with accessories, with the pouch accessory component being shown separately from the hoodie component and in a folded state;
FIG. 9 is a front elevational view of the pouch accessory component of the hoodie with accessories of FIG. 8;
FIG. 10 is a rear elevational view of the pouch accessory component of the hoodie with accessories of FIG. 8;
FIG. 11 is a left side elevational view of the pouch accessory component of the hoodie with accessories of FIG. 8;
FIG. 12 is a right side elevational view of the pouch accessory component of the hoodie with accessories of FIG. 8;
FIG. 13 is a top plan view of the pouch accessory component of the hoodie with accessories of FIG. 8;
FIG. 14 is a bottom plan view of the pouch accessory component of the hoodie with accessories of FIG. 8;
FIG. 15 is a perspective view of the hoodie component and the pouch accessory component of the hoodie with accessories, wherein the pouch accessory component is in an

(Continued)

unfolded state and attached to a front side of the hoodie component, with a rear side of the pouch accessory component facing front;

FIG. 16 is a front elevational view of the hoodie and the pouch accessory component of the hoodie with accessories of FIG. 15;

FIG. 17 is a left side elevational view of the hoodie and the pouch accessory component of the hoodie with accessories of FIG. 15;

FIG. 18 is a perspective view of a hat accessory component of the hoodie with accessories, with the hat accessory component being shown separately from the hoodie;

FIG. 19 is a front elevational view of the hat accessory component of the hoodie with accessories of FIG. 18;

FIG. 20 is a rear elevational view of the hat accessory component of the hoodie with accessories of FIG. 18;

FIG. 21 is a left side elevational view of the hat accessory component of the hoodie with accessories of FIG. 18;

FIG. 22 is a right side elevational view of the hat accessory component of the hoodie with accessories of FIG. 18;

FIG. 23 is a top plan view of the hat accessory component of the hoodie with Accessories of FIG. 18;

FIG. 24 is a bottom plan view of the hat accessory component of the hoodie with accessories of FIG. 18;

FIG. 25 is a perspective view of a card holder accessory component of the hoodie with accessories, with the card holder accessory component being shown separately from the hoodie;

FIG. 26 is a front elevational view of the card holder accessory component of the hoodie with accessories of FIG. 25;

FIG. 27 is a rear elevational view of the card holder accessory component of the hoodie with accessories of FIG. 25;

FIG. 28 is a left side elevational view of the card holder accessory component of the hoodie with accessories of FIG. 25;

FIG. 29 is a right side elevational view of the card holder accessory component of the hoodie with accessories of FIG. 25;

FIG. 30 is a top plan view of the card holder accessory component of the hoodie with accessories of FIG. 25;

FIG. 31 is a bottom plan view of the card holder accessory component of the hoodie with accessories of FIG. 25; and,

FIG. 32 is an exploded front view of the hoodie, the pouch, the hat and the card holder accessory components of the hoodie with accessories with the pouch, the hat and the card holder accessory components being displayed separately from each other and the pouch accessory component being in a folded state.

The dashed broken lines of the hoodie component shown separately from the hoodie with accessories in FIGS. 1-7 define portions of the hoodie component that form no part of the claimed design. The dashed broken lines of the pouch accessory component shown separately from the hoodie with accessories in FIGS. 8-14, as well as attached to the hoodie component in FIGS. 15-17, define portions of the pouch accessory component that form no part of the claimed design. The dashed broken lines of the hat accessory component shown separately from the hoodie with accessories in FIGS. 18-24 define portions of the hat accessory component that form no part of the claimed design. The dashed broken lines of the card holder accessory component shown sepa-

rately from the hoodie with accessories in FIGS. 25-31 define portions of the card holder accessory component that form no part of the claimed design. The dashed broken lines of the hoodie, pouch, and card holder accessory components of the hoodie with accessories in FIG. 32 define portions of the articles that form no part of the claimed design. The dash-dot-dash broken line in the view of FIG. 24 defines the bounds of the claimed design of the hat accessory component, and forms no part of the claimed design.
